(57) **CLAIM**

The ornamental design for a horticulture grow light, as shown and described.

DESCRIPTION

FIG. 1 is a perspective view of a horticulture grow light, as viewed from below, showing my new design;

FIG. 2 is a perspective view of the light shown in FIG. 1, as viewed from above;

FIG. 3 is a left side view of the light shown in FIG. 1;

FIG. 4 is a right side view of the light shown in FIG. 1;

FIG. 5 is a front elevation view of the light shown in FIG. 1;

FIG. 6 is a rear elevation view of the light shown in FIG. 1; FIG. 7 is a bottom plan view of the light shown in FIG. 1; and,

FIG. 8 is a top plan view of the light shown in FIG. 1. The broken line disclosure shown in the views is understood to represent portions of the article in which the claimed design is embodied, but which form no part of the claimed design. Where a broken line borders a claimed surface, that broken line is understood to represent an unclaimed boundary between the claimed and unclaimed surfaces.
